UNITED STATES PATENT OFFICE

JOHN FREDRIK HALSTEAD, OF BROOKLYN, NEW YORK, ASSIGNOR TO INTERNATIONAL CIGAR MACHINERY COMPANY, A CORPORATION OF NEW JERSEY

PREPARING CIGAR WRAPPERS

Application filed June 20, 1930. Serial No. 462,583.

This invention relates to a method of cutting and applying a wrapper to a cigar bunch and an improved wrapper cutting and applying mechanism for cigar machines, adapted to carry out said method, its main object being to so arrange the position of the wrapper cutting bed relative to the operator that the wrapper can be placed on the cutting bed in a manner that will favor its tight rolling around the cigar bunch in the wrapping mechanism, and avoid loose wrapping resulting when the cutting bed is placed in the usual manner. Another object is to so place the cutting bed relative to the operator that, in serving the wrapper, the inferior portion of the leaf section next to the stem, and not the best portion near the outer edge, will be wasted in the cutting operation. With these and other objects not specifically mentioned in view, the invention resides in certain methods, apparatus and machines which will be hereinafter fully described and then specifically set forth in the claims hereunto appended.

It has been well known for a long time that cigars wrapped in the usual manner are not wrapped perfectly, that is, the visible edge or overlap of the wrapper could not be wrapped tightly on the cigar bunch by the ordinary methods and apparatus employed for wrapping cigars. The cause of this was unknown, however, until I made the discovery that the operator of the cigar wrapping machine, in applying the tobacco leaf section to the wrapper cutting bed to be cut, unconsciously stretched the nearer edge of the leaf section with a greater tension than the further edge, although instructed to stretch both edges with equal tension. By my discovery it will be seen that when the nearer edge of the leaf section is so superstretched it results in a cigar having a loosely wrapped overlap in the cigar wrapper because this edge forms the overlap of the cigar as wrapped by ordinary methods and apparatus. To avoid these defects, I have invented a novel method and an improved apparatus which utilizes this unconscious stretching of the nearer edge of the leaf section by the operator to provide a cigar hav-

ing a tightly wrapped overlap in the wrapper.

In the ordinary types of suction-served cutting beds, the wrapper leaf, in being stretched upon the bed, becomes superstretched at the near edge and loose at the far edge so that, with the usual relative arrangement of cutting bed and wrapping mechanism, the superstretched side becomes the inner or covered edge of the wrapper while the loose side becomes the outer edge or overlap, resulting in a loosely wrapped cigar of inferior quality. Furthermore, the veins in the cigar leaf impose certain conditions in serving the bed which, with the ordinary arrangement of the bed and wrapping mechanism, necessitate the placing of the leaf in such position as to waste the best portion thereof in cutting the wrapper.

In the present invention, these difficulties are avoided by reversing the cutting bed so that the manipulation of stretching the leaf section on the bed causes the overlap edge of the wrapper to be superstretched and the covered edge to be relaxed, thus producing a tight lapping of the wrapper when applied to the cigar bunch in the wrapping mechanism.

When the leading or covered edge of the wrapper has been stretched on the cutting bed so that, in wrapping, it winds too tightly around the cigar bunch, the overlap edge cannot lie down snugly on the bunch. By reversing the construction, that is by so placing the cutting bed with respect to the operator to cause the trailing or overlap edge of the wrapper to be superstretched, the lap-joints on the cigar will always be tight, as then the leading edge, owing to its looseness, will permit the overlap edge to lie flat on the cigar bunch. A cigar so wrapped will have a better appearance and will not open up when smoked. Furthermore, the improved arrangement brings the finer portion of the leaf closer to the bed in serving, so that the waste is cut off the poorer portion. As there is no faulty tendency to overcome in serving the bed, the laying of the leaf section is much easier, and operators will require less time for learning.

Finally, the cutting operation will be more efficient because the reversed shape of the wrapper will suit the swing of the cutting rollers, the curvature of the "flag" now being convex to the roller swing while formerly it was concave to the same.

The reversing of the cutting bed, of course, necessitates a modification of the motion of the wrapper carrier, the same starting end of the wrapper now having to be brought from the opposite end of the cutting bed to the starting point of the wrapping operation, at the tail or "tuck" end of the cigar bunch.

In the accompanying drawings which form a part of this specification and in which like characters of reference indicate the same or like parts:

Fig. 1 is a perspective view showing a tobacco leaf being stretched on the cutting bed by the operator;

Fig. 2 is a diagrammatic view showing the path traveled by the wrapper from the cutting bed to the wrapping mechanism, the dotted lines showing the cutting bed in the ordinary position and the full lines in the reversed position;

Fig. 3 is a top view of a cigar covered by a wrapper on a cutting bed in the ordinary position, illustrating the effect of the stretching of the leaf on the tightness of the wrapper folds;

Fig. 4 is a top view showing a leaf section placed on a cutting bed which is in the ordinary position;

Fig. 5 is a top view showing the same leaf section placed on a cutting bed which is in the reversed position;

Fig. 6 is a plan view of a wrapper carrier provided with means for effecting the modified movement required by the reversal of the cutting bed; and

Fig. 7 is a side elevation of the mechanism shown in Fig. 6.

In carrying the invention into effect, there is provided a method of, and apparatus for, cutting and applying a cigar wrapper to a cigar bunch. In the best practice of the invention the method includes stretching a tobacco leaf section over a wrapper cutting bed with the edge which is to form the overlap on the bunch superstretched, then cutting out a wrapper from said leaf section, and then applying the wrapper to a cigar bunch. All the apparatus that is essential to the practice of the invention is a cutting bed positioned with its overlap side nearer the operator and a wrapper carrier unit arranged to take the cut wrapper and deliver it to a cigar bunch to be wrapped.

When an operator stretches a tobacco leaf on the cutting bed, the leaf section L, as shown in Fig. 1, for reasons explained below, is held with its far side raised so as to first make contact with the cutting bed D

at the side nearest the operator who then slides the leaf across the bed in order to spread it as evenly as possible before laying the remainder of the leaf. As the central portion of the near edge of the leaf comes to rest on the cutting bed, it is held fast thereon by the suction connected to the bed casing and acting on the leaf through openings O, so that the subsequent forward motion of the operator's hands, shown by the vertical arrows in Fig. 1, superstretches the leaf L in the direction of the horizontal arrows and causes the leaf to curve away from the operator, with the result that the far side of the leaf relaxes and, when cut into wrapper shape, often even becomes more or less wrinkled, according to the condition of the tobacco. But, even if the cut wrapper apparently lies perfectly flat on the bed, this curving effect of the progressive suction-hold is great enough to cause a considerable difference in the tension between the forward and rear edge of the wrapper thereby producing a variance from its true shape.

With the ordinary position of the cutting bed, shown in dotted lines in Fig. 2, the loose or relaxed edge of the wrapper, when applied to the cigar, forms the overlap edges of the turns, producing poor, partly open joints as shown in an exaggerated manner in Fig. 3. With the cutting bed reversed, as shown in full lines in Fig. 2, the super-stretched edge of the wrapper forms the overlap edge of the finished cigar while the relaxed edge is covered up by the super-stretched edge of the next turn, thus producing a tightly rolled cigar.

To produce a perfect cigar, the leaf section must be placed on the bed with its right or smooth side up and with the veins obliquely across the bed, pointing forwardly on the leaf from the flag end of the bed towards the tuck-end, and the portion of the leaf which covers the head-end, technically known as the "flag", must be free of veins. In order to comply with these conditions on a cutting bed as ordinarily placed, Fig. 4, the leaf section L must be gripped at its outer edge R and must be placed on the bed as far away from the operator as possible, so that the operator can watch the flag F while feeding the leaf and see that the same will be located on the bed with the flag between two veins. This procedure brings the stem-edge S of the leaf section close to the near side of the bed D and thus wastes the portion R of the leaf overhanging the far side of the bed, provided the overhang is not large enough to cut a second wrapper. With the bed reversed, Fig. 5, the leaf section L must also be reversed so as to have the veins run in the proper direction, and the leaf section will thus be gripped at the stem side S, causing the latter to overhang when the rim-edge R of the leaf has been

brought into final position close to the bed D. In this case, therefore, the outer or thin part of the leaf is used and the inferior stem-portion is wasted.

5 It has been sought to overcome the defects shown in Fig. 3 by the expedient of cutting the wrapper with its visible lapping edge substantially shortened from its true shape, so that, in applying the wrapper, more than 10 the provided length is required to fit properly around the cigar, thereby taking up the looseness produced by the curving of the leaf on the die. But, since the curving action produces varying results with different 15 operators, with different qualities of tobacco, and under different atmospheric conditions, this expedient only corrects the trouble for the average case assumed in laying out the modified shape; when the curvature 20 is greater than that assumed, the joints will still be loose, and when it is smaller, the wrapper will be too tight and may tear at the laps.

The heavy dash lines in Fig. 2 show the 25 path of the wrapper from the cutting bed at $F_1 T_1$ to the starting position $F_8 T_8$ at the tuck end of the cigar bunch C in the wrapping mechanism. The flag end of the wrapper moves along the path $F_1 F_2 F_3 F_4$ 30 making a part turn about its tuck end which at the same time moves along the path $T_1 T_2 T_3 T_4$. When it has arrived at F_4 , near the head or flag end of the cigar C, the flag end of the wrapper is carried along path $F_5 F_6$ 35 $F_7 F_8$ while the tuck end describes first a concave path $T_5 T_6$ and then a convex path $T_7 T_8$. From position $F_8 T_8$, the wrapper carrier returns in the reverse order, the 40 wrapper being applied to the cigar bunch while moving from $F_8 T_8$ to $F_4 T_4$, from which point the carrier returns empty to the bed position $F_1 T_1$ to pick up the next wrapper. In the old position of the bed, the 45 initial position of the wrapper is $T'_1 F'_1$ shown in dotted lines, the tuck end T'_1 taking the place of the flag end F_1 and the flag end F'_1 that of the tuck end T_1 . To reach the position $F_4 T_4$, from which the path of the wrapper must be the same as before so 50 as to pass along the cigar bunch in the proper positions for wrapping on its return path, the flag end moves along the approximately straight dotted path $F'_1 F'_2 F'_3 F'_4$ and the tuck end along the dotted path $T'_1 T'_2 T'_3 T'_4$ which joins the dash line path $T_4 T_8$, making a rather sharp turn.

The mechanism for performing the modified motion of the cut wrapper necessitated by the reversed position of the cutting bed 55 is as follows: The carrier unit is mounted on a hollow shaft 10 rotatable in the vertical bore 11 of a bracket 12 mounted on the bed plate 13 of the cigar machine. The upper end of shaft 10 is closed by a plug 14 while 60 its lower end is connected by a pipe, not

shown, to a suitable suction apparatus. On the upper end of hollow shaft 10 is clamped a hollow arm or support 15 which on its free end by means of shaft 16, supports the hollow carrier arm 17, rotatably mounted 70 on the former by means of bearings 18. The ends of the hollow joint between arms 15 and 17 are closed by the caps 19 and 20, respectively. The free end of arm 17 is formed into a vertical bearing 21 in which is rotatably held the hollow carrier head 22 so mounted as to communicate, through arms 17 and 15 and shaft 10, with the suction apparatus referred to. The head 22 has the interchangeable bottom portion 23 which is 75 formed to suit the shape of the wrapper to be applied and which is closed at its bottom by the detachable carrier plate 24 provided with rows of suitably placed holes for permitting the suction to pick up the cigar 80 wrapper from the cutting bed D when in position above the latter. The upper end of carrier head 22 is closed by gear 25 meshing with gear segment 26 pivoted on stud 27 supported by lug 28 of carrier arm 17. 85 The extending end of segment 26 forms the cam lever 29 carrying cam roller 30 guided in cam track 31 of a cam plate 32 mounted on carrier bracket 12. Carrier arm 17 has a cam lever 33 carrying roller 34 guided by 90 cam track 35 of the cam plate 32. The lower end of hollow shaft 10 carries gear segment 36 meshing with gear segment 37 pivoted on stud 38 held by bearing bracket 39 which is fastened to bed plate 13. Segment 37 is 95 provided with a cam lever 40 engaging by means of cam roller 41 in cam track 42 of cam 43 mounted on the main drive shaft of the cigar machine.

In the operation of the machine for carrying out the method, the carrier 23 must take the cut wrapper from the bed D to the wrapper applying position at the tuck end of the cigar bunch C located in the wrapping device, must guide the wrapper along the 100 cigar bunch while being wrapped and then go empty to its initial position over the bed D, along the path shown by the dash lines in Fig. 2. This is accomplished by a combination of the turning motion of hollow shaft 10 produced by gear segment 37, of the pivotal movement of arm 17 produced by cam lever 33, and of the turning motion of the carrier head 22 by the gear segment 26. Arm 15 on shaft 10 carries the pivot 105 end of arm 17 along a circular path, while at the same time the arm 17 swings around the moving pivot, and the carrier head 22 turns in the moving free end 21 of arm 17; all these movements being guided by the cam 110 tracks 31, 35 and 42 which are laid out for each cigar shape to give the carrier head its correct position and proper speed at every point of its path. The wrapper carrier is 115 provided with valves, not shown, which auto- 120

matically control the suction in the carrier head as required at the different stages of its motion. The carrier head 23 also communicates, through flexible pipe 44, with an air compressor, not shown, controlled by a valve which turns on compressed air to free the flag end of the wrapper from the carrier plate 24, in the position $F_4 T_4$ of the carrier head, at the moment when it leaves the 10 now finished cigar C to return to the cutting bed for the next wrapper.

What is claimed is:

1. The method of applying a wrapper to a cigar bunch, which consists in stretching 15 a leaf section over a wrapper cutting bed, superstretching the edge which is to form the overlap on the bunch, then cutting out a wrapper from the leaf section so stretched and superstretched, and then applying the cutout stretched and superstretched wrapper in that condition to a cigar bunch, to avoid looseness at the overlap of the wrapper.

2. The method of applying a wrapper to 25 a cigar bunch, which consists in stretching a leaf section over a wrapper cutting bed, superstretching the outer edge of the leaf which is to form the overlap on the bunch, then cutting out a wrapper from the leaf 30 section so positioned and stretched and superstretched, and then applying the cutout stretched and superstretched wrapper in that condition to a cigar bunch, to avoid looseness at the overlap of the wrapper and 35 to avoid using the inferior part of the leaf section.

3. The combination with a stationary 40 wrapper cutting bed provided with wrapper underlap and overlap sides positioned with the wrapper overlap side nearer the operator so that she will superstretch a leaf 45 section along that side, of means for taking a cutout wrapper from said bed and delivering it to a cigar bunch with the superstretched side of the wrapper forming the overlap on the bunch.

4. The combination with a stationary 50 wrapper cutting bed provided with wrapper underlap and overlap sides positioned with the wrapper overlap side nearer the operator so that she will superstretch a leaf section 55 along that side, of means for taking a cutout wrapper from said bed and delivering it to a cigar bunch with the superstretched side of the wrapper forming the overlap on the bunch, said means including a rotatable shaft, and cam means controlling 60 said carrier unit to move it to a position overlying the cutting bed to pick up the wrapper and deliver it to the cigar bunch.

5. The combination with a stationary 65 wrapper cutting bed provided with wrapper underlap and overlap sides positioned with the wrapper overlap side nearer the operator so that she will superstretch a leaf sec-

tion along that side, of means for taking a cutout wrapper from said bed and delivering it to a cigar bunch with the superstretched side of the wrapper forming the overlap on the bunch, said means including a rotatable shaft, a support mounted on said shaft, a carrier arm pivotally mounted on said support, a wrapper carrier head rotatably supported in said arm, cam operated gear means for rotating said shaft and head respectively, and cam means for swinging said carrier arm about its pivot on the support.

In testimony whereof, I have signed my name to this specification.

JOHN FREDRIK HALSTEAD.
